(57) CLAIM

The ornamental design for a china cabinet, as shown and described.

DESCRIPTION

FIG. 1 is a left front perspective view of a china cabinet showing my new design;

FIG. 2 is a side elevational view, the opposite side being a mirror image thereof; and,

FIG. 3 is a front elevational view thereof.

The views of the china cabinet not shown form no part of the claimed design. The dashed lines represent environmental elements only and form no part of the claimed design.

1 Claim, 3 Drawing Sheets
